BOTTLE STORAGE RACK

George R. Staten, Columbus, Ohio, assignor to George Staten, Inc., Columbus, Ohio, a corporation of Ohio

Filed Apr. 23, 1963, Ser. No. 74,584

Term of patent 7 years

(Cl. D58—26)

FIG. 1 is a front elevation of a bottle storage rack, showing my new design;

FIG. 2 is a transverse, vertical sectional view taken along the line 2—2 of FIG. 1;

FIG. 3 is a top plan view thereof;

FIG. 4 is a rear elevational view thereof; and

FIG. 5 is a side elevational view thereof.

The side of the bottle storage rack not shown is a mirror image of the side shown in FIG. 5.

I claim:

The ornamental design for a bottle storage rack, substantially as shown and described.
